BIMETAL TANK

Arthur J. Kercher, Berkeley, Calif.

Application April 5, 1938, Serial No. 200,132

3 Claims. (Cl. 220—63)

This invention relates generally to the manufacture and construction of metal tanks and containers, and is of value where the usage to which such devices are subjected, is apt to cause detrimental corrosion.

In the past non-corrodible tanks and containers have been made from relatively expensive metals and metal alloys, which, as distinguished from ordinary steel or base metal, are substantially non-corrodible for the service desired. For example copper, brass or bronzes have been used to a considerable extent, and more recently the so-called stainless alloys, such as Monel metal. All such metals or alloys are comparatively expensive, and in addition their use may involve manufacturing difficulties. It has been attempted to provide non-corrodible liners for base metal tanks, without notable success. For example electroplating and application of sprayed metal have been employed. Such coating methods are not reliable because it is difficult to secure a protective layer of adequate thickness, uniformity and density, and because insufficient latitude is available with respect to the composition of the liner desired. Furthermore technical difficulties are involved, which add to the cost of manufacture. It has also been proposed to apply a sheet metal liner of non-corrodible metal, such as copper, to steel tanks. The methods and constructions used in the past however have failed, because the liners have been subject to stresses when in use, to cause failure and ultimate leakage.

It is an object of the present invention to provide a simple bi-metal tank or container, which will make use of available sheet metal stock of non-corrodible metals or metal alloys, for lining a base metal shell. It is another object of the invention to provide a novel method of manufacture, whereby such bi-metal tanks can be made in quantities with a high degree of uniformity, and without the possibility of undue stresses being applied to the liner when the tank is in use.

Further objects of the invention will appear from the following description in which the preferred embodiment of the invention has been set forth in detail in conjunction with the accompanying drawing.

Referring to the drawing:

Fig. 1 is a side elevational view, showing a bi-metal tank incorporating the present invention.

Fig. 2 is an enlarged cross-sectional detail, showing the form of the liner when initially applied to the base metal shell.

Fig. 3 is an enlarged cross-sectional detail, showing one stage in the method of manufacture, in which corrugations in the end edges of the liner, are removed.

Fig. 4 is an enlarged cross-sectional detail, showing the manner in which a connection or fitting can be applied to one side wall of the tank.

Fig. 5 is an enlarged cross-sectional detail, showing the manner in which the liner is pressed against the side walls of the tank, when internal pressure is applied.

Fig. 6 is an enlarged cross-sectional detail, showing one stage in forming an end junction between the cylindrical side walls of the shell, and one end wall.

Fig. 7 is a view similar to Fig. 6, but showing another stage in the manufacture, in which the end edge of the shell is turned or bent inwardly.

Fig. 8 is a view similar to Fig. 6, but illustrating a final stage in making the joint between the side and end walls.

In carrying out the present invention I employ a relatively inexpensive base metal, such as cold rolled steel, to form a strong outer shell. Assuming that a relatively simple tank is being formed, the outer shell consists of cylindrically formed side walls 10, together with upper and lower end walls 11. The inner surfaces of the side walls 10 are covered with a sheet metal liner 12, formed of relatively non-corrodible material such as copper or Monel metal. The end walls 11 are dished inwardly as shown in Figs. 6 to 8 inclusive, and their inner faces are also covered by the liner portion 13.

In making the liner portion 12 for the cylindrical side walls, I prefer to proceed as follows: A sheet of the non-corrodible metal is first cut to proper size, and then bent to substantially cylindrical form, and the side edges suitably joined together to form a seam. This seam may employ two locking edges crimped together, as is well known by those skilled in the art, and suitable hard solder can be applied to insure against leakage.

The diameter to which the liner is initially formed is somewhat greater than the internal diameter of the cylindrical shell. For example for a shell having an internal diameter of about twelve inches, the circumference of the liner can be oversize to the extent of about $\frac{3}{8}$ of an inch. The liner is then placed in a suitable corrugating machine, and a plurality of corrugations 14 provided which extend throughout the length of the liner. In practice I have used corruga-

tions of about $\frac{1}{4}$ inch in depth, with a spacing between valleys in the neighborhood of $\frac{3}{4}$ of an inch. It will be apparent however that such dimensions may vary and are not critical. The corrugations should be such that the effective outside diameter of the liner is substantially reduced to a value less than the internal diameter of the shell. The liner can now be introduced into the cylindrical side walls of the shell, without difficulty.

The length of the cylindrical portion of the liner is somewhat less than the length of the side walls 10. For example with tanks of the order of 12 or 14 inches in diameter, the cylindrical liner portion 12 can be proportioned so that the side walls of the shell extend beyond the ends of the liner for a distance of say $\frac{3}{4}$ of an inch.

The next operation is to remove the corrugations from end margins 12a of the liner. This can be done by a simple rolling operation, which necessarily involves some compression of the liner, to eliminate all evidence of corrugations. It will be evident that such a rolling operation causes the marginal portions 12a to snugly contact the adjacent surfaces of the shell. Assuming now that the corrugations have been removed from both end margins of the liner portion 12, the end walls 11 can now be applied. The liner portion 13 for the end walls 11 can be shaped to snugly fit the end walls, by a suitable spinning operation. Note particularly that one margin edge 13a, extends over the flange 15.

The end walls 11 are so proportioned that when applied as shown in Fig. 6, there is a relatively snug fit so that the marginal edge portions 12a and 13a are gripped between the flanges 15, and the side walls 10. Note that there are edges 12c, 13c of the liner, which project outwardly beyond the flange 15. These edges can be bent inwardly as shown, to facilitate the soldering operation to follow.

The next step is to bend the projecting edges 16 of the side walls 10, to afford annular recesses 17. This bending can be carried out by a rolling or peening operation, and should be such that the reduced internal diameter encompassed by the edge 18, is substantially less than the diameter of the flanges 15.

The next operation is to braise or fuse the liner margins 12a and 13a together, and to also cause these margins to be bonded to the adjacent portions of the shell. In carrying out this fusing or braising operation, it has been found convenient to slowly rotate the tank, while a blow torch is applied to the bent portion 16 of the shell, to heat the same to an elevated temperature. After a suitable temperature has been reached hard solder or spelter is applied to the recess 17, together with suitable fluxing material, whereby the spelter or hard solder penetrates to bond together the faces of liner margins 12a and 13a, and to bond together these margins to the adjacent surfaces of the base metal. Sufficient excess spelter is applied to form a filler 19 for the recess 17, within which the edges 12c, 13c are embedded. It will be apparent from Fig. 8 that this filler of hard solder forms in effect an annular key between the end portions 16 and the end walls 11, whereby the end walls are firmly held in place against internal pressure, and whereby any internal pressure is effectively transmitted from end walls 11 to the side walls 10. While fused spelter is being applied the projecting edges 12c, 13c facil-

tate the production of a strong liquid tight joint, with penetration of the spelter between the surfaces interposed between flanges 15 and the shell.

Suitable fittings can also be provided in both the end and side walls of the tank. For example fittings 21 or spuds can be provided in the end walls 11, for making connection with liquid pipes. Such fittings should be made of relatively non-corrodible metal or metal alloy, and in addition to being sealed with respect to the liner, they should be firmly bonded to the stronger metal of the shell. Such fittings, if required, are preferably applied to the end walls before these end walls are secured to the side walls, in the manner previously described. To apply a somewhat similar fitting 22 to the side walls, the corrugations must be removed from an annular portion 12b of the liner 12, thereby providing a substantially flat surface for bonding to the inner flange 23 of the spud, and to the adjacent base metal surfaces.

After forming the tank as described above, an internal hydraulic pressure is applied to test the same against leakage. The pressure applied is of such a value as to definitely reshape the corrugations in the liner portion 12. Thus as illustrated in Fig. 5, internal pressure has forced the liner portion 12 outwardly against the adjacent walls of the shell, whereby portions 12c of the liner are definitely in contact with the adjacent walls of the shell, while portions 12d remain as corrugations. With the corrugations 12d remaining throughout the life of the shell, it will be apparent that internal pressure applied to the tank, or circumferential expansion and contraction, can not subject the liner to disruptive stresses. In fact with internal pressure the liner is always subjected to circumferential compression, rather than tension. Thus adequate bearing is provided between the liner and the adjacent cylindrical walls of the shell, without imposing objectionable stresses upon the liner, and this is all accomplished without tedious fitting of the liner into the shell.

It will be evident that the bi-metal tank described above can be manufactured at reasonable cost. In most instances it can take the place of expensive tanks or containers, constructed entirely of non-corrodible metal. The manner in which the sealed joints are formed at the ends of the tank, does not involve the application of heat by flame or arc, directly to the metal liner. Thus there is no danger of striking or otherwise distorting or damaging the liner by excessive direct heating, and any stresses which may be temporarily developed during the fusion operation, are absorbed by the steel shell.

This application is a continuation in part of my co-pending application, Serial Number 73,269, filed Apr. 8, 1936.

I claim:

1. In a bi-metal tank, a base metal shell having end walls and cylindrical side walls, a non-corrodible sheet metal liner extending over the inner surfaces of the shell, the junction between each end and the side walls of the shell having marginal edge portions of the liner interposed between the same, and each end edge of the cylindrical side walls extending past the edge of the adjacent end wall being turned inwardly to overlap the adjacent end wall and form an annular recess, said annular recesses being filled with hard solder.
2. In a bi-metal tank, a metal shell formed of

relatively corrodible sheet metal, said shell including substantially cylindrically-shaped side walls and end walls fitted within the side walls, the end walls being dished inwardly, a comparatively non-corrodible sheet metal liner extending over the inner surfaces of the shell, said liner including side portions extending over the side walls of the shell and end portions extending over the end walls of the shell, said side and end portions of the liner having cylindrical shaped overlapping margins interposed between the side and end walls of the shell, said overlapping margins having their contacting faces bonded together to form a sealed joint and also having their inner and outer peripheral surfaces bonded to adjacent surfaces of the shell, the end edges of the shell extending beyond the adjacent edges of the end walls and being bent inwardly to form annular recesses adjacent the end edges of the liner, said recesses being filled with hard solder thereby locking the ends to the side walls of the shell.

3. In a bi-metal tank, a metal shell formed of relatively corrodible sheet metal, said shell including substantially cylindrically-shaped side walls and end walls fitted within the side walls,

the end walls being dished inwardly, a comparatively non-corrodible sheet metal liner extending over the inner surfaces of the shell, said liner including side portions extending over the side walls of the shell and end portions extending over the end walls of the shell, said side portions being formed of corrugated sheet metal with the corrugations extending longitudinally with respect to the tank, said side and end portions of the liner having cylindrically-shaped overlapping margins interposed between the side and end walls of the shell, said margins of said side portions being free of said corrugations, said overlapping margins having their contacting faces bonded together to form a sealed joint and also having their inner and outer peripheral surfaces bonded to adjacent surfaces of the shell, the end edges of the shell extending beyond the adjacent edges of the end walls and being bent inwardly to form annular recesses adjacent the end edges of the liner, said recesses being filled with hard solder, thereby locking the ends to the side walls of the shell with said solder providing for transmission of endwise thrust on said end walls to said side walls.

ARTHUR J. KERCHER.
